attorney.

UNITED STATES PATENT OFFICE.

LEWIS W. HEMP, OF ST. LOUIS, MISSOURI, ASSIGNOR TO JAMES HALPIN,
OF SAME PLACE.

RADIATOR FOR HEATING-FURNACES.

SPECIFICATION forming part of Letters Patent No. 250,354, dated December 6, 1881.

Application filed August 17, 1881. (No model.)

To all whom it may concern:

Be it known that I, LEWIS W. HEMP, a citizen of the United States, residing at the city of St. Louis, in the State of Missouri, have invented certain new and useful Improvements in Radiators for Heating-Furnaces; and I do hereby declare that the following is a full, clear, and exact description of the same, reference being had to the accompanying drawings, forming a part of this specification.

My invention relates to certain improvements in that class of radiators which are used in connection with heating-furnaces; and the objects of my improvements are, first, to provide a simple, cheap, and effective construction of radiator, whereby a more effectual heating of the air is accomplished without retarding the draft through the same to any great degree; second, to afford facilities for regulating and controlling the draft through the radiator; and, third, to provide a means for readily cleaning the radiator when choked up with soot, &c. I attain these objects by the mechanism illustrated in the accompanying drawings, in which—

Figure 1 is a vertical section of my improved radiator. Fig. 2 is a horizontal section at line *x x*, Fig. 1; and Fig. 3 is a detail section, showing the arrangement of circulating heater-pipes.

As shown in the drawings, this invention consists of an inclosing-casing, A, having an opening, *a*, communicating with the outlet of the furnace B, which furnace may be of any suitable form and construction.

Within the radiator-casing A is arranged a bell-mouthed diaphragm, C, that forms a partition within the chamber, as clearly indicated in Fig. 1, the object being to direct the currents of heated air, &c., upward and outwardly, and then downwardly through the opening *c*, and backwardly through the outlet flue or opening D. By this means I am enabled to produce a very effective circulation of the heated products of combustion within the radiator, and thereby fully realize the proper effect of the heat from the furnace, and that with but very little obstruction to the draft.

It is evident that while the passage or open-

ing *c* is shown as diametrically opposite the outlet-opening D, yet the position of the said opening may be varied (by turning the diaphragm) so as to suit the draft of the chimney to which the invention is applied. With a good draft it can be located directly opposite the outlet-opening D, while with a poor draft it can be changed relatively nearer to the outlet-opening.

E represents a series of heating-pipes passing from the bottom to the side of the radiator, as clearly indicated in Fig. 3, the purpose of which is to form a circulating-heater for the air that is used in heating the building, and which is contained within the casing of the furnace.

F is an opening or hand-hole formed in the side of the radiator for the purpose of removing any accumulation of soot, &c., from the interior of the same.

G are partitions arranged before the outlet-flue D, as shown, and provided, one or both, with a damper, *g*, by which the draft can be regulated and guided to one or the other side of the radiator.

Having thus fully described my said invention, what I claim as new, and desire to secure by Letters Patent, is—

1. A radiator for heating-furnaces, consisting of a casing, A, bell-shaped partition or diaphragm C, opening *c*, and inlet and outlet openings *a* D, as described, and for the purpose set forth.

2. A radiator for heating-furnaces, consisting of a casing, A, bell-shaped partition C, opening *c*, partitions G G, damper *g*, and inlet and outlet openings *a* D, as herein described, and for the purpose set forth.

3. A radiator for heating-furnaces, consisting of a casing, A, bell-shaped partition C, opening *c*, and heating-tubes E, as described, and for the purpose set forth.

In testimony whereof I have hereunto set my hand, at St. Louis, Missouri, this 13th day of August, 1881.

LEWIS W. HEMP.

In presence of—

ROBT. BURNS,
H. A. BRIDGES.
